US00D908986S

(12) **United States Design Patent** (10) Patent No.: **US D908,986 S**
(45) Date of Patent: ** Jan. 26, 2021

(54) **CLOTHING CARE MACHINE**

(71) Applicant: **Samsung Electronics Co., Ltd.**, Suwon-si (KR)

(72) Inventors: **Hyunwoo Yoon**, Seongnam-si (KR); **Sanghun Yoon**, Seoul (KR); **Jinsook Park**, Uiwang-si (KR); **Sodam Park**, Seoul (KR); **Kangkyung Lee**, Seoul (KR)

(73) Assignee: **Samsung Electronics Co., Ltd.**, Suwon-si (KR)

(**) Term: **15 Years**

(21) Appl. No.: **29/680,099**

(22) Filed: **Feb. 13, 2019**

(30) **Foreign Application Priority Data**

Aug. 16, 2018 (KR) 30-2018-0038076

(51) LOC (13) Cl. **15-05**

(52) U.S. Cl.

USPC **D32/6**

(58) **Field of Classification Search**

USPC D32/1-3, 5-6, 10, 25
CPC D06F 58/20; D06F 73/02; D06F 58/10;

D06F 58/12; D06F 58/203

See application file for complete search history.

(57) **CLAIM**

We claim the ornamental design for a clothing care machine, as shown and described.

DESCRIPTION

FIG. 1 is a front perspective view of a clothing care machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view taken along line 8-8 of FIG. 2; and,

FIG. 9 is a cross-sectional view taken along line 9-9 of FIG. 2.

The broken lines in the figures depicting portions of the clothing care machine form no part of the claimed design.

1 Claim, 9 Drawing Sheets
